UNITED STATES PATENT OFFICE.

CHARLES HALLAIRE, OF AMSTERDAM, NEW YORK.

CURTAIN-SHADE BRACKET.

1,153,069.

Specification of Letters Patent.

Patented Sept. 7, 1915.

Application filed October 9, 1914. Serial No. 865,917.

To all whom it may concern.

Be it known that I, CHARLES HALLAIRE, a citizen of the United States, residing at Amsterdam, in the county of Montgomery and State of New York, have invented new and useful Improvements in Curtain-Shade Brackets, of which the following is a specification.

This invention relates to improvements in combined shade roller brackets and curtain supports, and the primary object of the invention is to simplify and improve the existing art by producing a device of this class which shall be longitudinally adjusted to compensate for the various sizes of shade rollers and curtain poles, and which will be also of simple construction, cheap to manufacture, strong and durable and thoroughly efficient in operation.

A further object of the invention is to provide a longitudinally adjustable shade roller bracket with a removable curtain pole support and to provide a novel communication between said bracket and support, so the support, when applied to the bracket will be retained against lateral or swinging movement and form a permanent fixture with the bracket, but capable of being easily removed when not desired in connection with the shade roller bracket.

With the above recited objects in view, and others which will appear as the nature of the invention is more fully understood, the improvements reside in a construction, combination and arrangement of parts set forth in the following description and falling within the scope of the appended claims.

In the accompanying drawing, Figure 1 is a perspective view illustrating the device supporting a window shade and curtain pole. Fig. 2 is a detail perspective view of the improvement. Fig. 3 is a transverse sectional view on the line 3—3 of Fig. 2. Fig. 4 is a horizontal sectional view on the line 4—4 of Fig. 3. Fig. 5 is a transverse sectional view on the line 5—5 of Fig. 3. Fig. 6 is a detail sectional view showing a modification of the manner of securing the base plate to the window frame.

Referring to the drawings, the numerals 1 and 2 designate a pair of elongated base plates, adapted, as shown in Fig. 1, to be positioned at the upper ends on the stiles 3 and 4 of the window frame. Each of these base plates has its opposite ends offset in the direction of the window frame as shown at

3 and 4, and then terminally extended in the opposite directions and parallel with the main body of the plate and provide attaching flanges 5 and 6, which rest against the adjacent stile of the window frame and are secured thereto by suitable fastening means 7 which extend through openings in the flanges and enter the window frame.

The base plates 1 and 2 are adapted to support a pair of shade roller brackets 8 and 9, each of which consists of a vertical base portion 10 constructed from a flat piece of material, and a horizontally projecting arm 11 formed integral with one of the vertical pawls of the edge portion, the free end of the said arm being provided with a concavo-convex disk shaped head 12 which is concentrically provided with an aperture 13 for the reception of one of the trunnions 75 of the shade roller. These brackets are adapted to move longitudinally over the base plates, and, as shown, the upper and lower ends of each are bent to provide U-shaped guides 15 which loosely receive the adjacent 80 base plate and form a retaining means for the bracket, and also permit unobstructed movement of the bracket on the plate. Each bracket arm 11 carries a pair of laterally extending flanges 16 and 17, which are formed 85 integral with the upper and lower longitudinal edges of the said bracket arm, and, as shown, have their free ends extended a slight distance beyond the concaved face of the adjacent head 12 and are provided with 90 registering openings 18 and 19, the said flanges having their terminals bent and extended in opposite directions to provide ears 20 and 21.

Each of the shade roller brackets has removably associated therewith a curtain pole bracket 22, which consists of a vertical portion 23 and a horizontal arm 24 having one end formed integral with the upper end of the vertical portion, and has its free end 100 projecting beyond the adjacent head 11 of the curtain bracket, and offset downwardly to provide a seat for one end of the curtain pole. When the curtain pole bracket is associated with the shade roller bracket the vertical portion 23 is adapted to be received by the registering openings 18 and 19 in the flanges 16 and 17 and the horizontal arm 24 is adapted to have one side engage against the head 12 and the opposite side is adapted 105 to engage the adjacent side of the upper ear 20, whereby the horizontal arm will be pre-

vented from having lateral movement when in position.

It will be seen from the above described structure that I have provided a combined shade roller and curtain pole bracket that may easily be disassociated when it is not desired to employ the curtain pole bracket, and also when it is desired to employ the curtain pole bracket the same may readily be associated with the shade bracket, and positively held against any lateral movement thereon.

In the modification shown in Fig. 6, the offset members 5 and 6 for spacing the base plate 1 from the window casing are done away with, and instead a washer 25 is interposed between the rear face of the base plate and the window frame and held in position by means of the attaching screw 7 which passes through an opening in the base plate and the washer.

What I claim as new is:

1. In a device of the class described, the combination with a base plate adapted for attachment to a window frame, a shade bracket adjustably mounted on the base plate and provided with a head, and a pair of laterally projecting lugs arranged one above the other and located in rear of the head and having registering openings, the

free terminals of the lugs being bent in opposite directions, a curtain pole bracket interposed between one side of the head and the bent terminal of one of the lugs and having a depending portion extending through the openings in the lugs, as and for the purpose specified.

2. In a device of the class described, the combination of a stationary base plate adapted for attachment to a window frame and having a bracket adjustably mounted thereon and having guides engaging over the longitudinal edges of the base plate, relatively flat members interposed between the base plate and the window frame and extending parallel with the base plate and frame and serving to hold the base plate spaced from the window frame and to engage the guides to limit the adjustments of the brackets in one direction, and means extending through the base plate and the spaced members and engaging the window frame whereby to hold the various parts in position.

In testimony whereof I affix my signature in presence of two witnesses.

CHARLES HALLAIRE.
